[57] CLAIM

The ornamental design for a control knob for chair
tilting mechanism, as shown and described.

DESCRIPTION

FIG. 1 is a side elevational view of a control knob for
chair tilting mechanism embodying my new design all
sides being identical and the mechanism being shown in
broken lines for illustrative purposes only;

FIG. 2 is a bottom plan view thereof; and,

FIG. 3 is a top plan view thereof.

FIG. 1

FIG. 2

FIG. 3
